EXHAUST FOR FLUID OPERATED TOOLS

Filed Sept. 25, 1929

INVENTOR.
Charles M. Stewart.

BY

R. H. Stew.

ATTORNEY.

UNITED STATES PATENT OFFICE

CHARLES M. STEWART, OF DENVER, COLORADO, ASSIGNOR TO GARDNER-DENVER COMPANY, OF DENVER, COLORADO, A CORPORATION OF DELAWARE

EXHAUST FOR FLUID OPERATED TOOLS

Application filed September 25, 1929. Serial No. 395,138.

In certain types of pneumatic tools, it is the advantageous custom to utilize exhaust ports that open rearwardly from the barrel. Where these tools are hand-held and directed, 5 the result is that the exhaust is delivered toward the handle and toward the operator. This is objectionable.

The object of the present invention is to provide a novel, simple and effective means 10 for deflecting the exhaust away from the operator.

In the accompanying drawings:

Figure 1 is a side elevation of an embodiment of the invention in place on a tool. 15 Figure 2 is a cross sectional view on an enlarged scale and taken on the line 2-2 of Figure 1.

Figure 3 is a longitudinal sectional view on the line 3-3 of Figure 2.

Figure 4 is a plan view of the deflector hood blank.

In the embodiment disclosed the tool consists of the usual barrel 5 having a rear head 6 secured to the rear end of the barrel by side 25 bolts 7. The rear head is provided with a handle 8. It is believed to be unnecessary to disclose and describe the tool as the structure is well-known and may be altered in various ways. It is thought sufficient to show 30 the exhaust ports 9 and 10 opening through the rear portion of the barrel, the ports 9 facing rearwardly and therefore directing the exhaust toward the handle 8 of the tool.

To deflect the exhaust a hood is employed 35 preferably formed of sheet metal, and comprising a body 11 having side walls 12 and connected at its rear end to an anchoring ring 13 by a forwardly tapering neck 14. The ring 13, as illustrated in Figures 1 and 2 is 40 placed between the rear end of the barrel 5 and the head 6 and is clamped thereby to more securely hold it in place. The ring is provided with ears 15 through which the side 45 bolts pass. The side walls 12, as shown in Figures 1 and 2, are bent inwardly and arranged in rearwardly divergent relation with their rear ends abutting the edges of the neck portion 14 and secured thereto by any suitable means, as spot welding. The side walls 50 have their free edges abutting the barrel on

opposite sides of the exhaust ports 9-10 and are secured thereto by suitable means, as for example, spot welding, indicated at 16.

With this structure, it will be evident that a hood is provided which overlies the exhaust 55 ports and is forwardly flared so that the air or other fluid discharging from the ports, is deflected forwardly and away from the operator.

From the foregoing, it is thought that the 60 construction, operation and many advantages of the herein described invention will be apparent to those skilled in the art without further description and it will be understood that various changes in the size, shape, 65 proportion and minor details of construction may be resorted to without departing from the spirit or sacrificing any of the advantages of the invention.

What I claim, is:

1. In a fluid operated tool, the combination with a barrel having an exhaust port, of a rear head for the barrel, and an exhaust deflecting hood covering the exhaust port and having an anchoring ring interposed between the barrel and head and clamped thereby.

2. In a fluid operated tool, the combination with a barrel having an exhaust port, of a rear head for the barrel, tie bolts securing the head and barrel together, and an exhaust deflecting hood covering the exhaust port and having a ring interposed between the barrel and head and having ears through which the tie bolts pass.

3. In a fluid operated tool, the combination with a barrel having an exhaust port, of an exhaust deflecting hood covering the exhaust port and having a rear end secured to the tool, and side walls abutting and secured to the barrel on opposite sides of the exhaust port.

4. In a fluid operated tool, the combination with a barrel having an exhaust port, of a rear head for the barrel, tie bolts securing the head and barrel together, and an exhaust deflecting hood covering the exhaust port and having a ring interposed between the barrel and head and having ears through which the tie bolts pass, said hood having

inturned side walls on opposite sides of the exhaust port and abutting the barrel.

5. In a fluid operated tool, the combination with a barrel having an exhaust port, of a rear head for the barrel, tie bolts securing the head and barrel together, and an exhaust deflecting hood covering the exhaust port and having an anchoring portion through which the tie bolts pass.

10 6. In a fluid operated tool, the combination with a barrel having an exhaust port, of an element secured to the barrel, tie bolts securing the element and barrel together, and an exhaust deflecting hood covering the 15 exhaust port and having an anchoring portion through which the tie bolts pass.

In testimony whereof, I affix my signature.

CHARLES M. STEWART.
